UNITED STATES PATENT OFFICE.

CHARLES C. SPREEN, OF DETROIT, MICHIGAN, ASSIGNOR TO KELVINATOR CORPORATION, OF DETROIT, MICHIGAN, A CORPORATION OF MICHIGAN.

MECHANICAL REFRIGERATION.

Application filed February 21, 1927. Serial No. 169,760.

My invention relates to mechanical refrigeration, and particularly to means for increasing the heat absorbing power of a refrigerant expansion unit, and the principal 5 object of my invention is to produce a new and improved means of this type. In the drawings accompanying this specification and forming a part of this application I have shown, for purposes of illustration, various 10 forms which my invention may assume, and in these drawings:

Figure 1 is a front elevation of one embodiment of my invention,

Figure 2 is a side elevation thereof,

15 Figures 3, 4, 5, are similar views showing other embodiments of my invention, while

Figure 6 is a section on the line 6—6 of Figure 4.

The embodiment of my invention shown 20 in Figures 1 and 2 comprises a plurality of containers 11 adapted to receive brine or other heat conducting material, and having openings 12 for introducing such heat conducting material. Each of the containers 25 11 is constructed with an aperture 13 extending entirely therethrough and of a size to fit closely over an expander drum 14 of a mechanical refrigeration system, and with a second aperture 15 disposed laterally of the aperture 13 and adapted to receive and support ice trays.

In the embodiment of my invention disclosed in Figure 3 there is shown a sleeve-like receptacle 16 passing through all of the 35 apertures 15 of the containers 11, and in Figures 4 and 5 there is shown a shelf 17 dividing the apertures 18 of a plurality of containers 19 into sections providing for supporting a plurality of ice trays 20 upon the 40 containers 19 and the shelf 17. Figures 4, 5, and 6 also show the containers 19 provided at their lateral edges, with laterally extending fins 21 which increase the heat conducting power of the containers 19.

45 From the above disclosure it will be obvious to those skilled in the art that I have provided new and improved means for increasing the heat absorbing power of a refrigerant expansion unit.

50 At the same time it will be obvious to those skilled in the art that the embodiment of my invention herein shown and described may be variously changed and modified without

departing from the spirit of my invention or sacrificing the advantages thereof, and it 55 therefore will be understood that the disclosure herein is illustrative only, and that my invention is not limited thereto.

I claim:

1. In a mechanical refrigerating system, a 60 cooling unit including a liquid refrigerant container, and a plurality of spaced parallel closed hollow brine receptacles surrounding said container, said receptacles having aligned apertures through which said container extends.

2. In a mechanical refrigerating system, a 65 cooling unit including a liquid refrigerant container, and a plurality of separate closed receptacles adapted to contain brine, said receptacles having aligned openings therethrough within their periphery through which said container extends.

3. In a mechanical refrigerating system, a 70 cooling unit including a liquid refrigerant container, and a plurality of separate closed brine receptacles through which said container extends and which are frictionally engaged thereby, said receptacles being formed with aligned openings remote from said container for the reception of a tray.

4. In a mechanical refrigerating system, a 75 cooling unit including a liquid refrigerant container, a plurality of closed brine containing receptacles, surrounding and frictionally engaging said container, said brine receptacles having aligned openings therethrough, and a tray receiving sleeve extending through the openings in said receptacles.

5. In a mechanical refrigerating system, a 80 cooling unit including a liquid refrigerant container, a plurality of separate closed brine containing receptacles surrounding and frictionally engaging said container, and fins extending from and attached to said receptacles.

6. In a mechanical refrigerating system, a 85 cooling unit including a liquid refrigerant container, a plurality of separate closed brine containing receptacles surrounding and frictionally engaging said container, and fins extending from and attached to said receptacles, said fins surrounding said container.

In testimony whereof I hereunto affix my signature.

CHARLES C. SPREEN.
